FIG. 1

FIG. 2

FIG. 1 is a front elevational view of a bowling lane masking shield showing our new design; and

FIG. 2 is a front elevational view of the masking shield of conventional thickness with the lights seen in FIG. 1 omitted for convenience of illustration.

The characteristic feature of our design resides in the particular overlapping pattern formed by the lights on the face of the masking shield.

We claim:

The ornamental design for a bowling lane masking shield, substantially as shown and described.
